STEP-BY-STEP SLIDE OPERATED PASTE
TUBE SQUEEZER

Canio B. Trotta, Newark, N. J.

Application October 5, 1948, Serial No. 52,872

4 Claims. (Cl. 222—103)

1

This invention relates to dispensers for tooth-paste, shaving cream, and the like, and aims primarily to provide certain new and useful improvements whereby the inconvenience of handling a tube of the paste are eliminated, and a practical and convenient means is provided for objecting a small quantity of the paste as desired.

The above broad as well as additional and more specific objects will be clarified in the following description, wherein characters of reference refer to like-numbered parts on the accompanying drawings. It is to be noted that the drawings are intended solely for the purpose of illustration, and that it is therefore neither desired nor intended to limit the invention necessarily to any or all of the exact details of construction shown except insofar as they may be deemed essential to the invention.

Referring briefly to the drawings, Fig. 1 is a front elevational view of the device.

Fig. 2 is a sectional view of the same taken on the line 2—2 of Fig. 1.

Fig. 3 is a sectional view taken on the line 3—3 of Fig. 1.

Fig. 4 is a sectional view taken on the line 4—4 of Fig. 2, with the tube of paste and the actuating slide member omitted.

Fig. 5 is a sectional view taken on the line 5—5 of Fig. 2, with the cover 15 and its block 22, however, shown elevation for the sake of clarity.

Fig. 6 is a perspective view of the actuating slide member per se.

Fig. 7 is a bottom plan view of the housing cover.

Referring in detail to the drawings, the numeral 10 indicates a housing substantially square in cross-section, having the rear wall 11, the side walls 12, and the front wall 13. All of the parts of the housing, as well as other parts about to be described, may be made of any suitable material, but preferably of a plastic material such as, for example, polystyrene. The bottom of the housing is closed by a floor 14, and the top, which is open, is provided with a removable cover 15 having a hand grip 16.

Both side walls 12 are provided on their inner surfaces with vertically spaced horizontal rails 17, each rail on one side lying in the same plane as one rail on the opposite side. The front wall 13 has a longitudinal slot 18 extending midway down the length of the wall, and at every horizontal level between successive tiers of coplanar rails this slot is widened into a circular opening 19. The length of the rails is less than the width of the side walls 12 thereby leaving vertical

2

spaces 17a between the ends of the rails and the front wall 13.

The floor 14 has an offset tapered opening 20 therethrough, adapted to have the neck of an inverted paste tube 21 register therein, as illustrated, after insertion of the latter into the housing through the top thereof.

The underside of the cover 15 is provided with a block 22 rigid therewith and of substantially the length and width of the housing interior cross-section, and near the rear end of the cover the block 22 has a transverse groove 23. The sealed end 24 of the tube 21 is adapted to register in the groove 23 when the cover is placed on the housing. Thus, by means of the groove 23 and the opening 20, the filled tube is centered or rather properly positioned and held in the housing.

The actuating slide for expelling paste from the tube, is shown at 25, and comprises a stem 26 adapted to slide through any round opening 19, an enlarged handle 27, and a cross-member 28 whose width exceeds the distance between the two rails of each co-planar pair of rails so that its extremities are adapted to slide between two vertically spaced pairs of rails 17. As illustrated, the cross-member 28 is shown in the shape of a yoke having the two arms 29, but if desired the latter could be omitted or the member 28 could be provided in the form of a flat plate, not shown, of the same length as the member 28.

Fig. 3 serves to illustrate the use of the slide member 25 in compressing the tube 21 so as to force the latter to expel paste from the tube when the cap 29a has been removed, and Fig. 3 is therefore believed to be proper to illustrate the invention. In actual use, however, that portion of the tube shown above the level of the slide 25 would appear substantially flat, since, in the manner described below, it has been flattened by the repeated act of compression by the slide member.

Referring again to Fig. 3, it is apparent that when the member 25 is pushed inward the cross-member 28 will tend to flatten the tube and thus cause paste to be expelled through the uncapped mouth of the tube, so that the expelled paste will be deposited on a brush, not shown, held thereunder. After each use of the device in that manner, the slide is left where it last was, except when the tube rearward of the slide has been completely flattened. Then, for use on the next occasion, the slide 25 is withdrawn part way until the reduced square-section 30 of the stem 26 is positioned within the vertical slot 18 and the

ends of the member 28 lie in the vertical spaces 17a forward of the rails, and since the section 30 is of sufficiently small width to move in the said slot, the slide member 25 is dropped a distance of one tier of rails into the horizontal spaces between the next successive lower rails. The slide is then used as above described to expel quantities of paste from that section of the tube in the same manner. When the entire tube has thus been flattened and hence substantially emptied, the slide is finally moved down into the open space 31 between the bottom of the front wall 13 and the floor 14, this space being provided by cutting the lower end of the front wall away to a height slightly in excess of the thickness, or height, of the cross-member 28. The cover 15 is then removed, the empty tube is extracted, the slide 25 is moved upward to the top space between the rails, and the full fresh tube is again inserted as before, and the device is then again ready for use.

A relatively wide plate 32 may be provided against the rear wall 11 for the purpose of attaching the device to the bathroom wall or a cabinet by passing screws through holes 33. A toothbrush holder such as shown at 34 may also be provided on the plate 32, and if desired other holding means, such as those for a razor or a brush, not shown, might also be added.

Obviously, modifications in form or structure may be made without departing from the spirit or scope of the invention.

I claim:

1. A device of the class described comprising a tubular vertical housing having a rear wall, a front wall, and side walls, said housing having a floor closing the bottom thereof, said floor having an opening therethrough, said front wall having the lower end thereof cut away to provide a space between said front wall and said floor, said side walls having vertically spaced horizontal rails on the insides thereof arranged in co-planar pairs, said housing being adapted to receive an inverted paste tube therein with the neck of said paste tube registering in said floor opening, said front wall having a vertical slot therethrough intermediate its width, and a slide member com-

prising a stem slidably mounted in said slot, that end of said stem positioned within the housing having a cross-member thereon, said cross-member having a width in excess of the horizontal distance between said rails the ends of said cross-member being selectively slidably mounted on any of said co-planar rails, said rails extending from said rear wall to a point spaced from said front wall thereby leaving on said side walls opposed vertical spaces, said vertical spaces having a width in excess of the width of said cross-member thereby permitting said cross-member to be moved vertically in said vertical spaces, the height of said first-named space being greater than the height of said cross-member, said stem adjacent said cross-member having a width less than the width of said slot.

2. The device set forth in claim 1, said slot having enlarged rounded cut-outs positioned between the mutually adjacent pairs of said co-planar rails, said stem having that portion thereof distant from said cross-member enlarged and of larger diameter than the diameter of said rounded cut-outs.

3. The device set forth in claim 1, said housing being adapted to receive an inverted paste tube therein as aforesaid, said housing having a cover adapted to cover the top thereof, said cover having a transverse slot in the underside thereof adapted to have the seam end of said tube register therein.

4. The device set forth in claim 1, said cross-member having yoke arms on the extremities thereof extending at right angles to said cross-member, said stem having a handle on the outer end thereof.

CANIO B. TROTTA.
